DESIGN FOR A PLAY DRESS

Dorothy Luntz, New York, N. Y.

Application April 23, 1940, Serial No. 91,878

Term of patent 3½ years

To all whom it may concern:

Be it known that I, Dorothy Luntz, a citizen of the United States and a resident of the city of New York, in the county of New York and State of New York, have invented a new, original, and ornamental Design for a Play Dress, of which the following is a specification, reference being had to the accompanying drawing, forming a part thereof.

Fig. 1 is a front view of the play dress with the hood attached, showing my new design.

Fig. 2 is a front view of the detachable hood shown in Fig. 1.

Fig. 3 is a rear view of the play dress shown in Fig. 1.

I claim:

The ornamental design for a play dress, substantially as shown.

DOROTHY LUNTZ.
